UNITED STATES PATENT OFFICE.

MARIO FERRAGUTI, OF BELGIRATE, ITALY.

METHOD OF AND APPARATUS FOR ARTIFICIAL FECUNDATION OF FLOWERS.

Application filed March 9, 1921. Serial No. 450,828.

To all whom it may concern:

Be it known that I, MARIO FERRAGUTI, a subject of the King of Italy, residing at Belgirate, Province of Novara, Piedmont, Kingdom of Italy, have invented certain new and useful Improvements in Methods of and Apparatus for Artificial Fecundation of Flowers, of which the following is the specification.

10 The present invention relates to an apparatus for the artificial fecundation of flowers, and especially of fruit-tree flowers, the apparatus being intended to prevent atmospheric agents, through an untimely or unsuitable action, bringing about the natural fecundation.

As well known, the main factors in natural fecundation are heat and wind. Now it naturally happens that these conditions do 20 not set in simultaneously or in proper succession or in proper intensity, the fecundation being prevented or reduced as a consequence.

The object of the present invention is to 25 supply an apparatus in which the said conditions are made to concur and can be controlled as may be required.

The annexed drawing shows, by way of example, one embodiment of the invention 30 which essentially consists in detaching the pollen from the anthers of the stamens by pneumatic action, in conveying the pollen through a heater in order to subject it to a determined temperature, in mingling it with 35 an inert substance that will act as a carrying medium, and in projecting it with a certain moderate pressure on the pistils of the same flowers from which it had been drawn.

For the said purposes in a kettle *a*, containing water that may be heated with a burner *b* fed in any convenient manner, is arranged the cylinder *c* of a double acting pump. A piston *d* which can be actuated from the outside by any suitable driving 45 gear, works in the cylinder *c*. Pipes *f*, *f'* and *g*, *g'* leading from the two cylinder-ends are fitted with suitable valves so that on each piston stroke a pressure chamber is formed in front of the piston forcing pressure-air into a delivery piping, and at the 50 rear of the piston a suction chamber is

formed drawing in air through a suction piping.

The delivery pipes *f*, *f'* join a single, preferably flexible, pipe or hose *F* secured to the 55 kettle *a*; likewise the suction pipes *g*, *g'* join together into a single pipe *G* which too is secured to the kettle *a*.

The two pipes *F* and *G* respectively terminate with nozzles *H* and *K*, the openings 60 of which are bell-mounted and facing each other as shown, a free space being left between the two; into this intermediate space the single flowers or clusters of flowers to be fecundated can be introduced. 65

At one end of the cylinder *c* a box *l* is arranged, containing a powdered substance, for instance talc or washed out ash mixed with iron sulphate or with lead arsenate, the 70 said powdered substance being drawn in across the valve *m* into the adjacent cylinder chamber during the suction stroke.

The working of the apparatus is as follows:

After so applying the apparatus that a 75 cluster of flowers is placed between the apertures of the nozzles *H* and *K*, the pump is started. Air is then drawn in through *K* and alternately carried into the two chambers into which the cylinder is divided by 80 the piston *d*. From these two chambers the said air is forced out alternately through the delivery nozzle *H*; on issuing from *H* the pressure air detaches the pollen from the anthers, and forces it into *K* from whence 85 it passes into the suction pipes and pump. Here it is heated and periodically mingled with the inert dust which acts as a carrying medium and is supplied by the box *l*. It is finally forced out through *H* and projected 90 against the pistils, to which it adheres.

The apparatus may be fitted with shoulder-straps so that it can be hung across a man's shoulder, or it may be arranged on a truck or the like. 95

Having now described my invention and how the same is to be carried out, what I claim as my invention is:

1. Apparatus for the artificial fecundation of flowers comprising a double acting 100 air pump, a pressure and a suction tube leading from the said pump, a funnel-shaped

mouth at the end of each of the said tubes, said mouths being opposite each other and suitably spaced apart, means for heating the said pump, an inert agent in the form of a finely powdered dust, and means for introducing the said agent into the said pump.

2. Process for the artificial fecundation of flowers consisting in removing the pollen

from flowers by means of induced air currents, conducting it to chambers where it is heated and mixed with an inert powder, and returning it again to the flowers. 10

Signed at Milan, Italy, this 16th day of February, 1921.

MARIO FERRAGUTI.
